UNITED STATES PATENT OFFICE.

BOUKA DE BOER, OF CORSICA, SOUTH DAKOTA.

GRAIN-SPOUT ADJUSTER.

1,149,899.

Specification of Letters Patent. Patented Aug. 10, 1915.

Application filed January 13, 1915. Serial No. 1,992.

To all whom it may concern:

Be it known that I, BOUKA DE BOER, a citizen of the United States, and a resident of Corsica, in the county of Douglas and 5 State of South Dakota, have invented a new and Improved Grain-Spout Adjuster, of which the following is a full, clear, and exact description.

This invention relates to improvements in 10 adjusting means for grain chutes or spouts, and has for an object to provide an improved construction adapted to be used in any place, especially on a thresher whereby the discharging chute may be moved to any 15 desired position and locked in said position.

Another object in view is to provide an 20 adjusting means for a grain chute which may be swung around a suitable pivot and locked at any point within its movement.

25 A further object of the invention is to provide a locking device for locking a grain chute in any position and means co-acting therewith for raising and lowering the discharge end of the chute.

30 In the accompanying drawings—Figure 1 is an enlarged detailed fragmentary side view of part of an elevator grain chute and mechanism embodying the invention; Fig. 2 is an enlarged detailed fragmentary side view of means for raising and lowering the discharge end of the chute; Fig. 3 is a section through Fig. 2 approximately on line 3—3; Fig. 4 is a sectional view through Fig. 2 on line 4—4; Fig. 5 is an enlarged 35 side view of the locking mechanism and associated parts embodying certain features of the invention; Fig. 6 is a top plan view of the structure shown in Fig. 5; Fig. 7 is a fragmentary sectional view on line 7—7 40 of Fig. 5.

Referring to the accompanying drawings by numerals, 1 indicates part of a threshing machine and 2 an elevator of any desired kind. Pivotedly connected near the top of the 45 elevator 2 is a grain spout or chute 3 of substantially any desired kind, which spout or chute is provided with a valve or shut-off 4 near the lower end. It will be evident that the elevator and chute could be associated with other devices in addition to a threshing machine, as for instance an ordinary grain bin. However, when using a threshing machine it is designed to have the same continuously operate and therefore 50 continuously discharge grain therefrom. In order that the continuously discharged grain

may be loaded into different sacks or other suitable receptacles in small quantities, it is necessary to move the chute or spout 3 on its pivotal bearing 5 which may be of any 60 desired kind. As the discharge will not instantly fill the sack or bag it is necessary to hold the spout or chute 3 stationary for an appreciable time in order that the sack or receptacle may be filled. To obviate the 65 necessity of employing a person continually for holding the spout in proper position, means have been provided for locking the spout quickly in any desired position. The gate or valve 4 is used for temporarily shutting off the grain while the chute is being 70 moved from one position to another.

As shown in Figs. 1, 5 and 6, a semi-circular rack 6 is provided which is bolted or otherwise rigidly secured to the elevator 2, 75 and which is provided with a flange 7 having spaced notches 8 which form the rack and which are adapted to receive the legs 9 and 10 of a pivotally mounted frame 11. The pivotally mounted frame 11 is pivotally 80 mounted on the bracket 12 which is clamped by a suitable bolt to the bracing beam 13. The bracing beam 13 is provided with an eyelet 14 interlocking with the eyelet 15, which eyelet is pivotally connected with a 85 bracket 16 riveted or otherwise rigidly secured to the elevator 2. The frame 11 is provided with an upwardly extending arm 17 to which one end of spring 18 is connected, the opposite end of spring 18 being connected with a stop or eyelet 19 secured to the beam 15. Spring 18 is a retractile spring and tends to continually hold the legs 9 and 10 in engagement with the notches 8 of the rack 6 and thereby prevent a swinging of 90 the bracing beam 15 and the chute 3 with which it is connected. The outer end of beam 15 is provided with a tongue 20 (Fig. 3) and a pair of bearing sides 21 and 22 which rest upon the lower surface of the flanges 23 and 24 of the guide 25, while the tongue 20 fits into the groove 26 of the guide 25. The outer end of the beam 13 is provided with a lock or eyelet 27 which receives the cable 28, said cable 28 passing over a pulley 29 and 100 extending outward to a suitable cleat 30 around which it is wrapped or tied in any suitable manner for preventing a downward movement of the outer end of the beam 15. 105

When it is desired to raise the chute or spout 3, cable 28 is pulled until the end car-

rying tongue 20 is raised to the desired extent. A reverse movement of the various parts will of course allow a lowering of the end of the chute or spout 3. Usually the 5 spout or chute 3 is adjusted to a certain height before the grain is allowed to be discharged therefrom and is left in that adjustment for an indefinite time while the chute is swung back and forth as occasion 10 may demand.

In order to allow a person near the lower end of the chute or spout 3 to quickly move the spout a pivotally mounted arm or crank 31 is arranged on the spout 3 to which is 15 connected a cable 32. Cable 32 passes over pulley 33 mounted on the outer end of beam 15 and has the inner end connected with the lower part of frame 11 so that when the crank or lever 31 is moved upwardly or 20 away from the spout 3 frame 11 will be moved pivotally out of engagement with rack 6, whereupon the spout or chute 3 may be moved to the desired position after which the crank 31 is released and frame 11 will 25 automatically engage the rack 6 under the action of spring 18. The cable 32 may be of any desired structure but usually adjacent the frame 11, the same being formed as a chain so that any of the links may be 30 caught or hooked over the hooked member 34 arranged at the lower end of the frame 11, whereby the slack in the cable may be taken up easily.

In operation the parts are adjusted, for 35 instance, substantially as shown in Fig. 1, and when it is desired to move the chute to one side so as to discharge to another receptacle crank or lever 31 is raised and frame 11 moved out of engagement with rack 6. 40 The chute or spout is then manually swung to one side after which crank 31 is released which will allow spring 18 to cause legs 9 and 10 of frame 11 to engage rack 6. This will lock the chute against any further 45 swinging movement. If for any reason it is desired to raise or lower the chute cable 28 is actuated so as to raise or lower the outer end of bracing beam 15.

What I claim is—

50 1. In a device of the character described, the combination with a pivotally mounted grain chute, of a guiding track arranged thereon, said track being formed with a groove, a pivotally mounted bracing beam 55 having a nose fitting into said groove, means

for supporting the outer end of said beam, said means being used to raise the outer end of said beam for adjusting the height of the outer end of the chute, and a locking member connected with said beam and with 60 the chute for locking the beam and chute against a horizontal swinging movement.

2. In a device of the character described, the combination with a chute, of a pivotally mounted bracing beam for supporting the 65 outer end of the chute, means for locking said bracing beam and the chute in any desired position and against horizontal swinging movement, said means including a stationary rack, a member acting as a catch 70 pivotally mounted on the beam, and adapted to engage said rack, and an operating member extending to a position adjacent the lower end of the chute.

3. In a device of the character described, 75 the combination with a swinging chute, of means for locking the same in any adjusted position, said means comprising a bracing bar, a rack formed with a plurality of notches, a swinging catch member pivotally 80 mounted on said bracing bar and formed with a pair of arms adapted to fit into said notches when the same is in a locked position, a spring acting on said catch member for causing the same to normally engage 85 said rack, and manually operated means extending to a position near the lower end of said chute for releasing said catch member temporarily.

4. In a device of the character described, 90 the combination with a swinging chute, of means for locking the chute in any adjusted position, said means comprising a bar for supporting the lower end of the chute, a pivotally mounted catch arranged on said bar, a 95 spring for urging said catch in one direction, a stationary rack adapted to be engaged by said catch whereby the catch and the bar cannot move, and a cable extending from said catch to a point near the lower 100 end of said chute, said cable being adapted to be manually operated for releasing said catch when it is desired to swing said chute.

In testimony whereof I have signed my name to this specification in the presence of 105 two subscribing witnesses.

BOUKA DE BOER.
